TOY MOTORCYCLE WITH A DISMOUNTING
AND MOUNTING CYCLIST

Max Ernst, Nuremberg, Germany

Application November 7, 1949, Serial No. 125,984
In Germany March 30, 1949

6 Claims. (Cl. 46—107)

1

My said invention relates to a mechanical toy motor cycle driven by a spring motor.

An object of the present invention is to provide a toy motor cycle whose cyclist gets off when stopping the cycle and stands aside. After a certain time he jumps again upon his seat and the cycle goes on. The whole operation is repeated as long as the spring motor is working.

By way of example, a preferred embodiment of the invention is shown in the accompanying drawings, wherein—

Fig. 1 is a side view of the toy motor cycle and the cyclist;

Fig. 2 is a top view of the same;

Fig. 3 is a top view of the motor cycle showing the cyclist standing beside the cycle;

Fig. 4 is a side view of the spring motor and the driving mechanism of the cyclist when the latter is sitting;

Fig. 5 is a top view of the same;

Fig. 6 is a side view of the spring motor and the driving mechanism of the cyclist when the latter has got off;

Fig. 7 is a top view of the same;

Fig. 8 is a front view of the driving mechanism of the motor cyclist and his legs;

Fig. 9 is a top view of the motor cyclist's base plate with a guide slit;

Fig. 10 is a horizontal section of the cyclist's driving mechanism on the line X—X, Fig. 8, and

Fig. 11 is a vertical section of the cyclist's driving mechanism on the line X1—X1, Fig. 10.

Similar numerals refer to similar parts throughout the several views.

Referring particularly to the accompanying drawings the toy motor cycle 1 is equipped with a spring motor casing 2 mounted therein and said casing having an ordinary spring motor for moving the toy motor cycle forwardly in the usual way. Outside the spring motor casing 2, on the winding shaft 3 of the spring motor is secured an edge cam 4 which has on its inside two dog pins 5 and 6. Behind this edge cam 4, on the shaft 7 there is pivoted a double-armed lever 8 which has both a stop 9 extending outwards on the frontside and a lug 10 on the surface extending straightly downwards. On the frontside of the spring motor casing 2 is provided a shaft 11, on which is pivoted a toothed segment 12 with a lever-arm 13 extending downwardly and provided with a pin 14 projecting outwardly through an arcuate slit 15 of the spring motor casing 2. The lever-arm 13 and the double-armed lever 8 are connected with each other by a tie rod 16 adapted to enable a

swivelling motion. The upper side of the spring motor is provided with a bow 17 formed by flaps which are drawn out of the casing. This bow 17 bears the shaft 18 with the pinion 19 secured on the latter and engages with the toothed segment 12. An arcuate arm 20 arranged above the saddle 21 of the toy motor cycle and bearing a dog pin 22, is fixed at one end to the upper end of the shaft 18. A figure 23, the arms 24 of which are applied on a swivelling handle bar 25 is adapted to sit upon the saddle 21. This handle bar 25 provided with an opening is connected with a pivot 26 fastened to the motor cycle frame and protected against automatic releasing by a pin or screw cap. In order to make the cyclist get off the cycle and jump on again the following mechanism is provided. Within the cyclist's body 23 there is secured a base-plate 27 having upstanding side walls 28 and a bottom opening 29 as illustrated by Fig. 9. Through the walls 28 passes a square shaft 30 to which the upper legs 31 and 32 of the figure 23 are affixed. The lower legs 33 and 34 are connected with the upper legs by a lug that allows them a partial rotary motion to the back. On the base-plate 27 is provided a pin 35 bearing a partially rotating toothed segment 36, the teeth 37 of which are engaging with the partial toothed wheel 38 mounted on the square shaft 30 at a bow 39. For the purpose of restricting the angle of rotation considering the alternative motion of the partial toothed wheel 38 in the toothed segment 36 two lugs 40 are drawn out of one of the walls 28 as shown in Figs. 8 and 11. The toothed segment 36 has a slot 41 therein for the passage of the dog pin 22. On the pivot 42 there is mounted a double-armed lever 43 controlled by a spring 44. This lever 43 has intermediate its ends a cam-engaging surface 45 bent outwardly therefrom, whereas the lower part of the lever is bent angularly inwardly and serves as a crutch for the toy motor cycle while stationary. The toy motor cycle with a dismounting and mounting cyclist operates as follows:

By the application of power to the shaft 3 from an ordinary spring motor the toy motor cycle is put into motion while the cyclist is sitting on the toy motor cycle as shown in Figs. 1 and 2 and the edge cam 4 begins to rotate. After a certain time of running the rotating edge cam 4 comes into contact with the double-armed lever 43 controlled by the spring 44, presses on the surface 45 and moves the double-armed lever 43 downwardly as shown in Figs. 6 and 7. Thus the double-armed lever 43 that till then

was laying in a notch 46 of the motor casing moves out of the notch 46 and comes into contact with the floor. Thus the spring motor casing together with the toy motor cycle is lifted a little at the front end so that the running wheels 47 are elevated out of contact with the floor thereby bringing the toy motor cycle to rest while the spring motor continues to operate. The stationary state of the toy motor cycle lasts till the edge cam 4 will have come out of contact with the double-armed lever 43. The continuation of the rotating motion of the edge cam 4 effects that the dog pin 6 comes into contact with the lug 10 of the double-armed lever 8 and presses it upwards and backwards. Together with the double-armed lever 8 being guided back the tie rod 16 too is drawn back thus moving by means of the pin 14 the lever-arm 13 and the toothed segment 12 which now comes into the position as shown in Fig. 6. Thus the pinion 19 mounted in the bow 17 is caused to rotate too thus moving the plate 20 provided with the dog pin 22. The cyclist sitting on the saddle 21 is now also engaged into a swinging motion. In order to obtain this motion the right leg 31, 33 of the cyclist must be lifted. For this purpose the right leg is adapted to move backwards. The back- and upwards movements of the right leg 31, 33 are obtained by means of the dog pin 22 which projects through both the slit 29 of the base-plate 27 and the slot 41 of the movable toothed segment 36 thus turning the latter as well as the partial toothed wheel 38 mounted on the bow 39. When the leg 31, 33 has reached the level of the saddle 21 the dog pin 22 of the semicircular plate 20 keeps the leg in an elevated position till the swivelling motion of the plate 20 will be finished. By this swivel the cyclist is also turned and loses contact with the saddle 21. By this swivelling movement of the cyclist the handle bar 25 being connected with the arms 24 of the cyclist, is turned likewise as illustrated by Fig. 3. The leg kept in an elevated position falls down by its own weight while the toothed segment 36 drives the dog pin again forwards. Now the cyclist stands beside the motor cycle. The leg 32, 34 is resting on the square shaft 30 so as to be driven and having always the same motion and position as the other leg. The toy motor cycle is still stationary. The mounting of the cyclist on the saddle takes place in the reverse manner as described in the following. While the edge cam 4 continues to rotate its dog pin 5 is pressed against the stop 9 thus moving the double-armed lever 8 upwardly. The lower side of the lever 8 with the lug 10 is moved downwardly and rearwardly until the dog pin 5 will have lost contact with the stop 9. By this motion of the lower end of the levers both the tie rod 16 and the lever arm 13 fixed thereto are pushed rearwardly thus turning the toothed segment 12 in a reverse direction as well as the pinion 19 and the plate 20 provided with the dog pin, which plate is now once more swinging inwards. Simultaneously the right leg is pushed backwards. This is obtained by the dog pin 22 pushing backwards the toothed segment 36 fixed to the base-plate 27 whereas the partial toothed wheel 38 gearing with the segment is pressed forwards. Simultaneously with the elevating of the leg the base-plate 27 too is driven by the dog pin 22 so as to swing from its lateral position inwards and being set on the saddle. The handle bar 25 adjusts hereby itself

once more horizontally to the motor cycle frame. When the cyclist is being set on the saddle the elevated and outward turned leg 31, 33 is released by the dog pin 22 of the plate 20 by the forward turning motion of the toothed segment 36 and by the driving of the partial toothed wheel 38 mounted on the bow 39 thus causing the leg to fall down. The left leg of the cyclist is driven too and falls down, i. e. it has then just the same position as the right leg. Meanwhile the dog pin 5 of the edge cam 4 has lost contact with the stop 9. The cam-engaging surface 45 of the double-armed lever 43 is also no longer influenced by the edge cam thus effecting that the lower end of lever 43 is drawn upwardly by the spring 44 and inserts itself into the notch 46 of the lateral plates of the spring motor casing 2. The contact of the lever 43 with the floor is lost, the running wheels 47 of the motor cycle now stand on the floor so that a running of the toy motor cycle becomes again possible. Thereupon the standstill of the toy motor cycle and its going on running as well as the mounting and dismounting of the cyclist will be repeated till the motor will run off.

It is of course, to be understood that my invention is not limited to the specific embodiment thereof here shown and described for purposes of illustration only.

What I claim is:

1. A toy of motor cycle design comprising a frame, a spring motor casing on the frame housing a shaft adapted to be power-driven, front and rear supporting wheels, ground wheels driven by said shaft for propelling the toy, a figure cyclist shiftably mounted on the frame, a cam member rotated by said shaft and swivelling mechanism interposed between said cam member and figure cyclist for the mounting and dismounting of the cyclist relative to the frame.

2. A toy as in claim 1, wherein the swivelling mechanism includes a pivoted arm for the support of the figure cyclist, a gear and rack segment for swinging the arm, a lever having a rod connection with said rack segment and a pin on said cam member adapted to engage and move said lever for operation of the rack segment to effect said swivelling movement of the figure cyclist.

3. A toy as in claim 1, wherein the figure cyclist has a right leg of hinged sections, a key shaft supporting the upper end of the upper section of the leg and means for rotating said key shaft to elevate said leg during lateral displacement of the figure cyclist to clear said frame with the leg dropping to a dependent position with the cyclist standing at one side of the frame.

4. A toy as in claim 1, wherein the swivelling mechanism includes a pivoted arm for the support of the figure cyclist, a gear and rack segment for swinging the arm, a lever having a rod connection with said rack segment and a pin on said cam member adapted to engage and move said lever for operation of the rack segment to effect said swivelling movement of the figure cyclist, said ground wheels being mounted at the forward end of the motor casing and a tensioned arm pivoted on the motor casing and adapted to be lowered into floor contact by said cam to elevate the forward end of the casing and ground wheels for bringing the toy to rest during mounting and dismounting activities of the figure cyclist.

5. A toy as in claim 1, wherein the figure cyclist has a right leg of hinged sections, a key

shaft supporting the upper end of the upper section of the leg and means for rotating said key shaft to elevate said leg during lateral displacement of the figure cyclist to clear said frame with the leg dropping to a dependent position with the cyclist standing at one side of the frame, said ground wheels being mounted at the forward end of the motor casing and a tensioned arm pivoted on the motor casing and adapted to be lowered into floor contact by said cam to elevate the forward end of the casing and ground wheels for bringing the toy to rest during mounting and dismounting activities of the figure cyclist.

6. A toy of motor cycle design comprising a frame, a spring motor casing on the frame housing a shaft adapted to be power-driven, front and rear supporting wheels, ground wheels driven by said shaft for propelling the toy, a figure cyclist shiftably mounted on the frame, a cam member rotated by said shaft and swivelling mechanism interposed between said cam member and figure cyclist for the mounting and dismounting of the

5 cyclist relative to the frame, said ground wheels being mounted at the forward end of the motor casing and a tensioned arm pivoted on the motor casing and adapted to be lowered into floor contact by said cam to elevate the forward end of the casing and ground wheels for bringing the toy to rest during mounting and dismounting activities of the figure cyclist.
